UNITED STATES PATENT OFFICE

2,522,023

JACKET FOR MATERNITY DRESSES

Barton H. Eason, McRae, Ga.

Application December 4, 1946, Serial No. 713,879

2 Claims. (Cl. 2—108)

1

This invention relates to a jacket for maternity dresses.

The primary object of the invention is to provide a jacket of the type described in which all points of expandable adjustment are fully concealed beneath portions of the jacket that are not in themselves capable of expansion.

Dresses of this type commonly embody the use of draw strings, overlapping fronts, or the like, and it has been found by those skilled in the art that these often do not present an appearance as neat as desired. It is an object of the invention to provide a jacket for a maternity dress which, by reason of a novel panel construction, will always present a neat appearance and which may, in fact, be worn subsequently to pregnancy if desired by reason of its straight-line panel formation, that conceals all points of expandable adjustment.

It is a further important object to provide a jacket for a maternity dress which will include a belted non-expandable front panel adapted to be dropped down over expandable portions of the garment, and adapted to conceal the points of expandable adjustment and also adapted to merge into the rest of the garment so as to conceal the fact that the jacket includes said swinging panel.

With the foregoing and other objects in view which will appear as the description proceeds, the invention consists of certain novel details of construction and combinations of parts, hereinafter more fully described and pointed out in the claims, it being understood that changes may be made in the construction and arrangement of parts without departing from the spirit of the invention as claimed.

Referring to the drawings

Figure 1 is a front view of a preferred embodiment of a maternity dress embodying the improved jacket constructed in accordance with the invention.

Figure 2 is a rear view.

Figure 3 is a front view, in which a panel front embodied in the invention is shown lifted away from the portions of the dress which it conceals while the jacket is being worn.

Figure 4 is a view taken on line 4—4 of Figure 1.

Figure 5 is a view taken on line 5—5 of Figure 3.

Referring to the drawing in detail, the character reference numeral 5 designates a wrap-around skirt that is adjustable as to its waist by

2

means of suitable fasteners 6, of which there may be any desired number. The skirt is made, as may be seen by referring to Figure 4, to overlap as at 7, this being in the nature of a conventional maternity dress skirt design.

The dress further includes a jacket 8 that may be fastened at the front with suitable ties 9, and which is expandable by means of pleats 10 that are pressed into the jacket at the front adjacent the ties 9. By reference to Figure 4, it may be noted that additional pleats 11 are included at the back of the jacket 8, but these do not ordinarily serve any purpose beyond suitable ornamentation, although they may if necessary permit further expandable adjustment of the jacket.

Sewed to the jacket 8 at the shoulder seams 12 thereof are the upper edges of a front panel 13, to which there may be sewed an ornamental bow 14 and which is preferably provided with pleats 15. To this front panel 13 there are sewed the ends of a belt 16.

As is clearly shown by Figure 3, the front panel 13 slips over the head of the wearer and falls across the front of the jacket as a straight-line front, after which one of the free ends of the belt 16 is passed around the back of the jacket 8, and both free belt ends tied adjacent the front panel 13, as at 17. It may, of course, be desired to make the portion of the belt 16 that passes around the jacket 8 longer than the other belt portion.

The pleats 15 in the front panel 13 are not intended to permit expansion of the front panel. All expansion of the jacket 8, by reason of the novel design of my maternity dress, occurs in the jacket 8, in the portion thereof that is concealed behind the front panel. The front panel, therefore, is in the nature of an effective and novel disguise that conceals all the expansion adjustment points of the garment, and eliminates the necessity of draw strings, overlapping fronts, and the like, that are commonly used in maternity dresses.

Further, the front panel construction may be used in various types of maternity dresses, such as one-piece dresses, suits, dinner dresses, and others, with full effectiveness, and without departing from the spirit of the invention as claimed.

It is not intended to limit the invention to the embodiment thereof that has been shown in the drawings and described herein, since this is only a preferred embodiment, in a two-piece dress.

It is further worthy of note that a maternity dress made in accordance with my invention may be used without alteration throughout the entire

period of pregnancy, and can, if desired, even be used subsequently.

What is claimed is:

1. In a maternity dress a jacket provided with shoulder seams and opening at its front along a line extending vertically and centrally thereof to provide separated front jacket portions, separable means adjustably connecting said separated portions, elongated straight pleats extending vertically of each of said portions and disposed close to and spaced from said line of separation, and a front cover panel on said jacket extending from the shoulder seams thereof to the lower end of the jacket and overlying said jacket portions, the upper end of said panel being disposed within and stitched into the shoulder seams of the jacket to provide a unitary jacket-and-panel construction unchanged in shoulder seam appearance from a jacket not having said panel, said panel having straight vertical side edges, and belt sections cooperating to extend around the waist of a wearer and respectively connected to the front panel at locations disposed on opposite sides of the center line and spaced from the side edges thereof, each belt section crossing over and being unconnected to a side edge of said panel.

2. In a maternity dress a jacket provided with shoulder seams and opening at its front along a line extending vertically and centrally thereof to provide separated front portions, means spaced vertically of said jacket portions and each adapted to effect a separate, independent adjustable connection between said portions, elongated

5 straight pleats extending vertically of each of said jacket portions and disposed close to and spaced from said line of separation, and a front cover panel on said jacket extending from the shoulder seams thereof to the lower end of the jacket and overlying said jacket portions, the upper end of said panel being disposed within and stitched into the shoulder seams of the jacket to provide a unitary jacket-and-panel construction unchanged in shoulder seam appearance from a jacket not having said panel, said panel being otherwise non-connected to the jacket, said panel having straight vertical side edges, and belt sections co-operating to extend around the waist of a wearer and respectively connected to the front panel at locations disposed on opposite sides of the center line and spaced from the side edges thereof, each belt section crossing over and being unconnected to a side edge of said panel.

10 20 15 25 30 BARTON H. EASON.
